LADDER FOR ELEVATOR CAR EMERGENCY EXITS

John Russell Bray, East Williston, N. Y., assignor to Otis Elevator Company, New York, N. Y., a corporation of New Jersey

Application May 19, 1938, Serial No. 208,797

5 Claims. (Cl. 228—34)

The invention relates to ladders for emergency exits of elevator cars.

It sometimes happens that the elevator car is brought to a stop between floors. In certain of those instances, especially where the stop is an emergency one by application of the car safety brake, it is considered unsafe to attempt to bring the car to a floor to discharge any passengers that it may have. It is therefore desirable that some 10 way be provided to enable these passengers to get out of the car.

In installations where two or more elevator cars are operated in a common hatchway, the cars are usually provided with aligned emergency side 15 exits to take care of this situation. In the case of single elevator cars, such arrangement cannot be provided so that resort is had to emergency exits in the ceilings of the cars. Ladders are provided for the occupants of the car to climb up through 20 the exit. The present invention is directed to improvements in ladders for use in conjunction with ceiling emergency exits of elevator cars.

The object of the invention is to provide an emergency exit ladder which is of strong construction and which, when not in use, may be folded up 25 so as to permit it to be stored in a small space.

Features and advantages of the invention will become apparent from the following description and appended claims.

30 In the drawings:

Figure 1 is a fragmental view in section of a portion of an elevator car, illustrating in front elevation the preferred construction of ladder applied to the emergency exit;

35 Figure 2 is a side view of the same;

Figure 3 is a front detail view, with parts in section, of the ladder;

Figure 4 is a side view of the same;

40 Figure 5 is a section taken along the line 5—5 of Figure 3; and

Figure 6 is a section taken along the line 6—6 of Figure 3.

The ladder comprises an elongated tube of rectangular cross-section arranged in two sections 11 and 12 to form a pole. These sections are joined by a short tubular member 13 also of rectangular cross-section, arranged to fit within the sections 11 and 12. Member 13 is provided with a pin 14 secured thereto, which extends into an elongated 45 slot 15 in the bottom of upper section 11. Member 13 is arranged to slide within sections 11 and 12, the pin engaging the ends of the slot to determine the limits of motion.

Each section is provided with a plurality of 50 rungs 16. Each of these rungs is of the same con-

struction and is mounted in the same way in the tubular section. Therefore, only one of them will be described. The rung comprises a pair of levers 17 and 18 pivotally mounted on a pin 20 extending through the tube. The tubular section is provided with a slot 21 on each side to admit the lever to the inside of the tube as it is swung upwardly about its pivot, as indicated in dot-dash lines in Figures 3 and 4 for one of the levers. These slots are enlarged at their upper ends to facilitate the 10 extension of said levers when folded back into the section. When extended, the levers rest on the bottoms of the slots 21 and are also supported by lugs 22 formed on the hubs of the levers for engaging the inside walls of the tube. A lug 23 is 15 formed on the outside end of each lever to provide a foot guard to prevent the foot from sliding off the rung.

From the top of the upper section extends a pair of arms 25 and 26 for holding the ladder in place. 20 On the outer end of each arm is a lug 28 which extends through a sleeved aperture 30 in the elevator car ceiling, these apertures being provided adjacent the emergency exit opening 36. The spread of the arms is such as to provide a base 25 adequate to prevent the ladder from turning. These arms extend through slots 31 provided on opposite sides of the tubular section in alignment with slots 21, and are coaxially mounted on a pivot pin 32 extending through oppositely disposed 30 elongated slots 33 arranged on opposite sides of the tube at right angles to the slots 31. Each of arms 25 and 26 is formed at the bottom with a hook member 34 which hooks over tubular section 11 at the bottom of slots 31. This locates the 35 arms 25 and 26 in the proper angular relationship for inserting lugs 28 in apertures 30. A resilient supporting button 35 is secured to the bottom of tubular section 12 for wedging the ladder between the floor and the ceiling.

To take down the ladder, the bottom is pulled 40 from its wedged position and the lugs 28 removed from apertures 30. The bottom tubular section 12 is pulled off tubular section 11 and tubular section 13 is slid upwardly into section 11 until pin 14 45 is brought to a stop in the top of slot 15. The levers 17 and 18 are folded upwardly about their pivot pins into their tubular sections. Also, the arms 25 and 26 are lifted upward slightly to disengage the hook members 34 from the tube, the slot 33 being of sufficient length to permit this 50 movement. These operations may be readily accomplished by turning the sections upside down, whereupon these members will drop into these 55 positions. The arms 25 and 26 are then swung

about the pivot pin into alignment with the tube and permitted to drop into the tube. Slots 33 are of such depth as to stop the arms in position where a certain portion of them is exposed through slots 31 to enable them to be again lifted for erecting the ladder. The retracted position of one of the arms is indicated in dot-dash lines in Figure 3. In this way the operating parts of the ladder are folded and slid into retracted position within the tubular members, leaving only the outer surfaces of the tubular members exposed.

Thus the ladder, when not in use, is very compact and may be readily stored in any suitable available space as, for example, on the outside 15 of the car accessible by means of a removable or hinged panel or, for example, behind a section of the base-board 38, usually referred to as the kick plate of the car. A storage space for the ladder is illustrated in Figures 1 and 2 20 behind the kick plate, a portion of the bottom part of the side of the car being bulged outwardly slightly to form a pocket to receive the tubular members. This portion of the kick plate is removably secured to the car panel as by 25 screws 37.

When it is desired to use the emergency exit 36 to get passengers out of the car, the screws 37 are loosened and the kick plate is removed. The tubular sections are removed from their 30 storage space and the ladder is assembled by putting the tubular sections together and sliding tubular member 13 down into tubular section 12. Levers 17 and 18 are swung outwardly about their pivots to form the rungs, and the arms 35 25 and 26 are pulled upwardly and swung outwardly about their pivots in position where the hook portions 34 engage the sides of tubular member 11. The lugs 28 are then forced upwardly into apertures 30 and the bottom of the 40 ladder is wedged against the floor.

Thus it is seen that a collapsible ladder is provided which is of simple construction and therefore economical to manufacture, which, when not in use, may be stored in a small out of the 45 way space and therefore does not detract from the appearance or the carrying capacity of the elevator car, and which, when assembled in place, provides a rigid, safe means for the use of passengers in leaving the elevator car through the 50 emergency exit.

As many changes could be made in the above construction and many apparently widely different embodiments of this invention could be made without departing from the scope thereof, it is intended that all matter contained in the 55 above description or shown in the accompanying drawings shall be interpreted as illustrative and not in a limiting sense.

What is claimed is:

60 1. A ladder for an emergency exit in the ceiling of an elevator car comprising; a plurality of detachably joined sections forming a pole, said pole having a slot on each side thereof in its upper end and a plurality of additional slots on 65 each side thereof beneath said upper end, a lever pivotally mounted in each additional slot adapted to be swung into such slot for storing and when extended to form a step, and members pivotally mounted in said slots in the upper end of said 70 pole adapted to be swung into such slots for storing and when extended for fastening said pole to the ceiling of said car.

2. A ladder for an emergency exit in the ceiling of an elevator car comprising; a plurality of 75 detachably joined sections forming a pole, said

pole having step members on each side thereof, said step members being pivotally mounted in said pole and means being provided for supporting said members when in extended position, said pole being provided with slots out of which said step members extend and to permit said step members to be swung from extended position into said pole, the upper end of said pole having anchor members pivotally mounted therein for securing said pole to the ceiling of said car, 10 said pole being provided with slots through which said anchor members extend and to permit said anchor members to be swung from extended position into said pole, the bottom of said pole being arranged for engaging the floor of said 15 car to secure said ladder in place.

3. A ladder for an emergency exit in the ceiling of an elevator car comprising; a pole of two detachably joined sections, each of said sections having step members on each side of the pole, 20 said step members extending into said pole and being pivotally mounted therein and said pole being provided with slots through which said step members extend and for receiving said step members when swung in from extended position, 25 stops being provided for limiting the pivotal movement of said step members in their extended positions, the upper section of said pole having a pair of anchor members extending into said pole and pivotally mounted therein for securing said pole to the ceiling of said car, said upper section being provided with slots through which said anchor members extend and for receiving said anchor members when swung in from extended position, 30 the bottom of said bottom section being arranged for engaging the floor of said car to secure said ladder in place.

4. A ladder for an emergency exit in the ceiling of an elevator car comprising; a pole of two detachably joined sections, each of said sections 40 having step members on each side of the pole, said step members being pivotally mounted on pins extending crosswise of said pole and said pole being provided with slots through which said step members extend and for receiving said 45 step members when swung in from extended position, the upper section of said pole having a pair of anchor members pivotally mounted on a pin extending across the upper end of said section, each of said anchor members having 50 a lug formed on its outer end and said ceiling being provided with apertures adjacent said exit to receive said lugs, said upper section being provided with oppositely disposed slots to slidably support said pivot pin for said anchor members and with slots through which said anchor members extend and for receiving said anchor members when swung in from extended position, 55 and a resilient button on the bottom of said bottom section for engaging the floor of said car with said ladder in place to wedge said ladder between said ceiling and said floor.

5. A ladder for an emergency exit in the ceiling of an elevator car comprising; a center pole of two tubular sections detachably joined by a 65 socket member slidably secured in one of said sections to extend into the other, each of said sections having a plurality of rungs extending therethrough to form horizontal steps on each side of the pole, each of said rungs being in 70 the form of two levers having hooked ends and extending oppositely from said pole, said levers being pivotally mounted on a pin extending crosswise of said pole and said pole being provided with slots out of which said levers extend and 75

which are elongated to permit said levers to be swung into said sections from extended position, the upper section of said pole having a pair of arms pivotally mounted on a pin extending across the upper end of said section, each of said arms having a lug formed on its outer end and said ceiling being provided with apertures adjacent said exit to receive said lugs, said upper section being provided with oppositely disposed slots to slidably support said pivot pin for said arms and with slots out of which said arms extend and which extend to the top of the section to permit said arms to be swung into the section

from extended position, the depth of said pin slots being such as to render said arms accessible through their slots when folded back into said section, each arm also being provided with hook portions to engage said section at the bottom of the slots for said arms when said arms are extended to properly position said lugs to extend into said apertures, and a resilient button on the bottom of said bottom section of said pole for engaging the floor of said car with said ladder in place to wedge said ladder between said ceiling and said floor. 5
